OVERHEAT PROTECTION FOR STEAM REHEATERS

Paul R. Walter, East Orange, N. J., and John W. Thompson, Weymouth Heights, Mass., assignors to Combustion Engineering-Superheater, Inc., a corporation of Delaware

Application April 14, 1949, Serial No. 87,484

20 Claims. (Cl. 60—73)

1

This invention relates to means for protecting superheaters from damage by overheating and in particular for so protecting a superheater used for reheating the steam flowing between high and low pressure turbine elements.

The usual power generating station to which the invention may be applied comprises a steam generator which delivers steam to a multi-stage steam turbine. A superheater heats the steam flowing from the generator to the high pressure end of the turbine and a reheat superheater reheats the steam flowing from a high to a lower pressure stage of the turbine, or from a high pressure turbine to a low pressure turbine. Both the superheater and the reheater are usually associated with the steam generator and receive heat from the products of combustion of the fuel passing through the generator.

The steam turbines are provided with speed responsive governors which, when the speed of the turbine exceeds a predetermined amount, will cut off the supply of steam to the turbine. With the steam flow stopped in both the superheater and reheat superheater, the flow of the hot products of combustion over the superheaters will continue pending a stoppage of the fuel supply to the generator. Under these conditions both the superheater and the reheater may become destructively overheated unless means are provided to keep their metal temperatures approximately at their normal operating temperatures. For this purpose safety valves have been placed in the superheater outlet which will be opened by the increased steam pressure resulting from the steam flow stoppage and their opening will reestablish a sufficient flow through the superheater to keep its metal temperature at a safe limit. The reheat, however, has received its steam only from the high pressure turbine stage and when the steam was cut off to the turbine, the steam flow through the reheat ceased.

Heretofore when the reheated steam temperatures were relatively low, the reheat was placed in a zone of the boiler furnace where the temperatures of the products of combustion were relatively low and there was only moderate danger of overheating the metal by the products of combustion in the event of steam flow stoppage. But in late power generating stations the reheated steam temperatures may be as much as about 1000-1050 deg. F. and the reheaters are placed in hot temperature gas zones so that in such present-day installations the danger of overheating the metal of the reheat does prevail to a degree clearly calling for protective measures.

It is an object of this invention to provide novel means in a steam power station for protecting a reheat superheater from destructive overheating by maintaining a steam flow there-

2

through when the steam flow thereto from the steam turbine is interrupted.

Other objects and advantages will become apparent from the following description of an illustrative embodiment of the invention when taken in conjunction with the accompanying drawings wherein:

Figure 1 is a diagrammatic representation of a steam power generating station embodying one form of the invention, showing conduits and valves and controls therefor to direct steam flow through the reheat superheater upon interruption of steam flow through the high pressure steam turbine; and

Figures 2, 3, 4 and 5 are diagrams showing modifications of the controls utilized by the Figure 1 system.

The steam power station here represented comprises a steam generator generally designated as G having a furnace F and a steam and water separating drum D. This generator G has located in the setting thereof a superheater in two sections S1 and S2 and a reheat R, these elements S1—S2 and R illustratively being organized with other parts of the generator as disclosed by copending application Serial No. 56,381 filed in name of John Van Brunt on October 25, 1948; but as the description hereof proceeds it will become apparent that power stations utilizing steam generators of other forms also may be benefited by the improvements of our invention.

In the arrangement shown, steam from the generator G flows through superheater S1, S2 thence serially through the stages of a high pressure steam turbine T1 and thence through reheat superheater R and the stages of a low pressure steam turbine T2. C represents a condenser for the steam leaving T2. The condensate leaving condenser C is pumped by the usual means (not shown) back into the steam generator G.

The products of combustion of the fuel burned within the furnace F rise upwardly through the steam generator G in two parallel passes 1 and 2. An intermediate dampered pass 3 may be provided for by-passing some of the products of combustion from the furnace F around the other passes 1 and 2. Partitions 4 and 5 separate the bypass 3 from the passes 1 and 2 and the passes are bounded on their opposite sides by the front and rear walls 6 and 7 and the side walls 8 (of which there is but one shown, the other being opposite thereto) of the steam generator G which are substantial continuations of the furnace walls below.

Adjacent the top of the generator G is a horizontally inclined roof 9 and spaced therefrom a horizontally inclined partition 10 which connects to the top of bypass 3. The roof 9 and the

partition 10 together with the side walls 8 form passages which serve to conduct the gases from passes 1 and 2 separately to the generator outlet 11. Dampers 12 and 13 are located adjacent the rear end of partition 10 and serve to control the proportionate flow of the products of combustion through the passes 1 and 2.

As the aforesaid Van Brunt application Serial No. 56,381 explains, the walls of the furnace F are preferably lined with steam generating tubes 14, the tubes of the front and rear walls inclining inwardly and upwardly toward the center of the furnace in open relation forming a cooling screen for the combustion products passing therethrough, thence pass upwardly adjacent the sides of partitions 4 and 5 and thence below partition 10 to the steam and water drum D. By this arrangement the furnace wall tubes may serve as supports for partitions 4, 5 and 10.

As here utilized the steam superheater of generator G is arranged in two sections S1 and S2 and is located in major portion within pass 1. Saturated steam leaving drum D passes through pipe 15 into superheater inlet header 16 and thence flows through the superheater in the direction of the arrows to superheater outlet header 17. The first section S1 through which the steam flows comprises a multiplicity of sinuous coils arranged in parallel transversely of the gas flows through pass 1. The outlets of said coils terminate in a desuperheater 18 which serves as the inlet header for superheater section S2. Superheater S2 comprises a multiplicity of sinuous coils arranged in parallel transversely of the direction of gas flow leaving the furnace. Below pass 1 the coils of superheater section S2 extend completely across the depth of the generator G and connect at their outlet ends into outlet header 17.

The re heater R, located within pass 2, is provided with an inlet header 19 and an outlet header 20 and comprises a multiplicity of sinuous coils arranged in parallel transversely of the gas flow through pass 2.

For supplying generated steam to the power station turbines, the outlet header 17 of superheater S1 and S2 is connected by pipe 21 to the inlet of high pressure turbine T1 via valves 22 and 23 later to be described. The exhaust from turbine T1 is connected by pipe 24 through check valve 25 and desuperheater 26 to the inlet header 19 of re heater R. The outlet header 20 of re heater R is connected by pipes 27 and 28 to the inlet of low pressure turbine T2 through valve 29. The exhaust of turbine T2 is connected directly into condenser C. A safety valve 30 is connected to outlet header 17 of superheater S1—S2 and a safety valve 31 is connected into a continuation of pipe 27 beyond the connecting pipe 28 with respect to steam flow to turbine T2. Said pipe extension is provided beyond the safety valve 31 with a stop valve 32.

In the illustrative arrangement here shown, the steam pipe 15 leading to the inlet header 16 of superheater S1—S2 from the steam generator drum D is continued as pipe 33 through a shut off valve 34 thence through an automatically controlled valve 35 and into the pipe 24 leading from the exhaust of high pressure turbine T1 through desuperheater 26 to the inlet header 19 of re heater R. If desired a valved bypass connection 36 may be provided around the valve 35 newly added in accordance with this invention to permit passage (at proper times) of auxiliary cooling steam into the generator's re heater R.

Forming part of auxiliary steam supply facilities for the re heater R is a pipe connection 37 provided in pipe 33 beyond valve 34 with respect to steam flow, pipe 37 being connected to a pipe 38 which is supplied with valves 39 and 40 either side of the connection. The pipe 38 connects the desuperheater 18 intermediate sections S1 and S2 of the superheater to valve 39. A pipe 41 then connects to an associated valve 40 to supply steam from a main in the boiler house at a lower pressure than that delivered by the steam generator G.

Looking now at turbines T1 and T2, steam delivered from the steam generator G via superheater S1, S2 to the high pressure turbine T1 passes through earlier mentioned conduit 21 and valves 22 and 23. Valve 22 represents an automatic stop valve and is arranged to automatically close when the turbine exceeds a predetermined maximum speed. Valve 23 represents the turbine governing or inlet valve or valves which controls the steam supplied to the turbine and may be arranged to automatically close when the turbine exceeds a predetermined speed (usually lower than that at which valve 22 closes). The speed-responsive governor and associated means for automatically closing valves 22 and 23 to stop the flow of steam to the turbine T1 may be conventional and hence are not here shown in full detail.

In one well known arrangement of such means the named valves 22 and 23 may be held open against a spring (not shown) by a fluid under pressure responsive to turbine speeds acting on pistons in cylinders 42 and 42' which act on valve stems 43 and 43'. When the fluid in the cylinders reaches pressures corresponding to certain predetermined excess turbine speeds, the pistons will move the stems 43 downwardly to close the valves; but at other times the valves 22 and 23 remain open. Arms 44 and 44' are adjustably attached to extend from stems 43 and 43' of valves 22 and 23 and move therewith. The extended ends of arms 44 are provided with contacts 45 and 45' which during normal operation of the turbine, are spaced from stationary contacts 46 and 46'. But when the valve stem for either valve 22 or 23 drops to close the valve, the contacts 45 and 46 associated therewith engage and close a circuit here illustratively shown as being energized from conductors 47 and 48 between which an electrical control potential is maintained.

The earlier mentioned control valve 35 (between a cooling-steam source and re heater inlet 19) is provided with control means actuated by a solenoid 49, which when energized over either of the represented turbine valve switches 45—46 and 45'—46' acts to lift the stem 50 of valve 35 to open it and when deenergized permits the valve to close again (under the action of any suitable means such as a spring not shown). Solenoid 49 further may be connected with conductors 47 and 48 so as to be energized by the potential appearing therebetween upon closure of a manually operable switch 51, by means of which valve 35 may be manually opened if desired, as well as upon engagement of the contacts 45—46 associated with either of the turbine valves 22 and 23. Switch 51 may be used upon failure of contacts 45, 46 or, if valve 35 is to be opened during the starting up period of the steam generator then to maintain a steam flow through the re heater R.

A so-called intercept valve 29 in pipe 28 ahead

of low pressure turbine T2, with respect to steam flow, is arranged to automatically close when turbine T2 exceeds a predetermined speed thereby throttling or stopping the flow of steam into that turbine. As such arrangement is conventional only symbolic representation thereof is here made.

The operation of our improved protecting facilities for reheater R will now be explained. Upon substantial closure of intercept valve 29, safety valve 31 opens and steam flowing through the reheater R and pipe 27 will then discharge through the safety valve to the atmosphere thereby protecting the reheater R against overheating by reason of stoppage (at valve 29) of steam flow into the low pressure turbine T2.

When either valves 22 or 23 (or both) close due to excess speed of high pressure turbine T1, so as to cause contacts 45, 46 to close, the solenoid 49 becomes energized (from conductors 47-48) and thereby causes the valve 35 to open. With valve 34 open and valves 39 and 40 closed, steam (from generator drum D) will then flow from pipe 33 through the thus opened valve 35, into pipe 24, through desuperheater 26 and reheater R, pipe 27 and out through safety valve 31 into the atmosphere. Under these conditions check valve 25 prevents steam from flowing back into the high pressure turbine T1.

The metal of reheater R will thereby be kept at a safe temperature due to the cooling by the steam flowing therethrough. In the absence of the automatically opening valve 35, the reheater R would be cut off from all steam flow from the high pressure turbine T1 when the valves 22, 23 closed and could be destructively overheated. Overheating would be due to its location in a relatively hot zone of combustion products from furnace F, which location is necessary to achieve the high steam temperatures now required.

Moreover, upon the aforesaid closure of valves 22 or 23, the superheater S1-S2 is protected by the safety valve 30 which will thereupon open and permit a flow of cooling steam through the superheater.

If the steam for supplying the reheater R through valve 35 is taken directly from the drum D, its pressure may be too high for reheater R. To suitably reduce the pressure in the reheater, valve 35 and/or pipe 33 for conducting the steam to it from pipe 15, may be made small so as to incur a suitable pressure drop therethrough; or an orifice resistance may be inserted in pipe 33 ahead of valve 35 with respect to steam flow. When steam is supplied to pipe 33 either from desuperheater 18 via pipe 38 or from a boiler room pipe main via pipe 41 at lower than boiler pressure, the above mentioned resistance may be unnecessary. With such steam supply, valve 34 is closed. Check valves 62, 65 may be provided to prevent high pressure steam from drum D entering desuperheater 18 and boiler room header 41 and to prevent steam from desuperheater 18 entering boiler room header 41.

Obviously means other than the electrical solenoid 49 here disclosed may be employed to open valve 35 when valves 22, 23 close; one example of such other means including employment of the fluid means mentioned above for closing valves 22, 23, to simultaneously act on a diaphragm or piston within a cylinder (not shown) mounted on stem 50 of valve 35 to open said valve.

Should valve 32 be selected of a type similar to valve 35, similar means may be employed to simultaneously and automatically open valve 32.

For example, control means actuated by a solenoid 49' may be arranged to operate valve 32 and be connected (as through a manually closable switch 63) into the circuit of conductors 47, 48 with the solenoid 49' arranged in parallel with the solenoid 49 as shown. With such an arrangement (and when switch 63 is closed) the safety valve 31 need not be depended upon to open since venting of the steam leaving reheater outlet 20 via pipe 27 can then be effected through valve 32.

In some installations it may be desirable to delay the opening of valve 35 so as to establish a predetermined period of time before the reheater R receives steam from a source other than the high pressure turbine T2. To accomplish such delayed opening of valve 35, Figure 2 shows a delay-introducing switch 52 provided in the circuit, to the solenoid 49 of valve 35. In the illustrative form represented switch 52 is normally held open by a compression spring 52'; but at proper times is delayedly actuated to the closed position by a solenoid 53 through an armature 54, which armature extends from the switch contact bar through the solenoid to a piston in a cylinder 55. The cylinder head above the piston is provided with a needle valve 56 to therewith control the rate of influx of a fluid into the cylinder and thereby the rate of downward movement of the piston and the time delay in closing switch 52.

As above indicated, switch 52 is normally open. Upon closure of contacts 45'-46' of the turbine's inlet valve 23 in Figure 1 (designated as IV in Figure 2), current flows from control line 47 through conductors 47b, 47c, solenoid 53, and conductor 48a to control line 48. The solenoid being energized acts to close switch 52 but is delayed in doing so for a predetermined time by the slow moving piston in cylinder 55. Upon such delayed closure of switch 52 the control current flows from conductor 47b through conductors 47d and 47e, solenoid 49 and conductor 48b to line 48. Reheater steam admission valve 35 is now opened by the thus energized solenoid, to assure continued passage of cooling steam through the steam generator's reheater R.

But closure of contacts 45, 46 of the turbine's stop valve 22 (designated as SV in Figure 2) acts upon protecting valve 35 without any such delay. Such closure establishes a current flow from line 47 through conductors 47a, 47e, solenoid 49 and conductor 48b to line 48, and the valve 35 thus opens instantly in response to closure of the turbine's stop valve IV.

Other generally similar control arrangements are shown in Figures 3, 4 and 5 in each of which diagrams the circuits, switches and solenoids that are the same as those of Figure 2 carry the same designations as appear in Figure 2. Such common parts include the contacts connected to actuate delayed-action switch 52 and valve-opening solenoid 49, and the operation of these elements is the same as that described above for the operation of the same elements in Figure 2.

Each of Figures 3, 4 and 5 further includes provision for opening reheater venting valve 32 simultaneous with the opening of reheater steam admission valve 35. In each of said diagrams conductors 47f and 48c are provided to carry current from conductor 47b through solenoid 49' to line 48. Upon closure of contacts 45, 46 of the turbines inlet valve IV (valve 23 in Figure 1), reheater venting valve 32 will be instantly opened by solenoid 49'.

In Figure 4, a switch 57 is interposed in conductor 47 to interrupt the current flow to solenoid 49 and cause the consequent closing of valve 32. Switch 57 is mounted on stem 58 of a pressure responsive means 59. Means 59, here shown as a sylphon bellows, is connected by a pipe 60 into the reheat steam conduits (as via outlet header 20) so as to be responsive to the steam pressure within the reheat R. The contacts of switch 57 are normally closed at a positive pressure in the bellows 59, and may be adjusted to open at, for example, atmospheric pressure or under. Consequently when the reheat pressure falls to or below atmospheric, valve 32 is by solenoid 49 (then deenergized) permitted to close and prevent air flow into the steam piping through valve 32.

Further considering Figure 4, a check valve 61 may be provided in pipe 21 (Figure 1) beyond the valve 32, with respect to steam flow, which will act to prevent a back flow of air into pipe 21 through valve 32. With such check valve 61 it may not be necessary to utilize the pressure responsive switch 57 (of Figure 4) which closes valve 32 upon loss of pressure.

In Figures 3 and 4, when contacts 45-46 of the turbine's stop valve SV (device 22 of Figure 1) close due to excessive turbine speed, the valve 32 will not open but upon the instantaneous admission of steam through valve 35 to the reheat R, and the consequent pressure rise in the reheat, the safety valve 31 will open to release the steam flowing through the reheat.

Optionally, the valve 32 may be opened simultaneously with the opening of valve 35 by the circuits shown in Figure 5, which may be substituted in Figures 3 and 4. In Figure 5, the stop valve switch SV is provided with a second set of contacts 45a-46a, contact 45a being connected to line 41 and contact 46a to conductor 47b. Upon closing contacts 45a-46a current will flow through conductors 47b, 47f, solenoid 49' and conductor 48c to line 48, thereby instantaneously opening valve 32.

Since numerous changes may be made in the above described organizations and different embodiments of the invention may be made without departing from the spirit and scope thereof, it is intended that all matter contained in the above description or shown in the accompanying drawings shall be interpreted as illustrative and not in a limiting sense.

We claim:

1. In a system comprising a steam generator having a steam superheater and a steam reheat disposed therein to absorb heat from the combustion gases thereof, steam turbine apparatus including a high pressure stage connected to receive high pressure steam from the outlet of said superheater and arranged to discharge that steam at reduced pressure into the inlet of said reheat, said turbine apparatus further including a low pressure stage connected to receive said reduced pressure steam as discharged from the outlet of said reheat, a valve in the supply connection from the superheater outlet to the high pressure turbine inlet arranged normally to be at least partially open, and means responsive to turbine speed for effecting closure of that valve and resultant cut off of the high pressure turbine steam supply when said speed reaches a given value, the combination of means for protecting said reheat against overheating by said combustion gases in the event of a closure of said high pressure turbine supply valve and

consequent stoppage of flow through the reheat of said discharge steam from the high pressure turbine outlet, said protecting means comprising a venting valve establishing connection from the reheat outlet to the atmosphere and organized to be closed as long as said reduced pressure steam flows from the high pressure turbine outlet through the reheat into the low pressure turbine inlet, and means rendered effective upon closure of said high pressure turbine supply valve for then opening said venting valve allowing the high pressure steam contained in the reheat to gradually escape through said venting valve and expand within the reheat, thereby cooling the reheat by absorption of heat therefrom.

2. In a system comprising a steam generator having a steam superheater and a steam reheat disposed therein to absorb heat from the combustion gases thereof, steam turbine apparatus including a high pressure stage connected to receive high pressure steam from the outlet of said superheater and arranged to discharge that steam at reduced pressure into the inlet of said reheat, said turbine apparatus further including a low pressure stage connected to receive said reduced pressure steam as discharged from the outlet of said reheat, a valve in the supply connection from the superheater outlet to the high pressure turbine inlet arranged normally to be at least partially open, and means responsive to turbine speed for effecting closure of that valve and resultant cut off of the high pressure turbine steam supply when said speed reaches a given value, the combination of means for protecting said reheat against overheating by said combustion gases in the event of a closure of said high pressure turbine supply valve and consequent stoppage of flow through the reheat of said discharge steam from the high pressure turbine outlet, said protecting means comprising a source of steam other than the aforesaid turbine outlet discharge, a normally closed shut-off valve establishing connection from said other steam source to the reheat inlet, a venting valve establishing connection from the reheat outlet to the atmosphere and organized to be closed as long as said reduced pressure steam flows from the high pressure turbine outlet through the reheat into the low pressure turbine inlet, means rendered effective upon closure of said high pressure turbine supply valve for then opening said normally closed shut-off valve whereby then to supply steam from said other source to the reheat inlet, and means effective upon admission through said shut-off valve of said other source steam into the reheat inlet for then opening said venting valve thereby allowing that other source steam to pass as a coolant through the reheat for escape to atmosphere by way of the reheat outlet and the venting valve.

3. In a system comprising a steam generator having a steam superheater and a steam reheat disposed therein to absorb heat from the combustion gases thereof, steam turbine apparatus including a high pressure stage connected to receive high pressure steam from the outlet of said superheater and arranged to discharge that steam at reduced pressure into the inlet of said reheat, said turbine apparatus further including a low pressure stage connected to receive said reduced pressure steam as discharged from the outlet of said reheat, a valve in the supply connection from the superheater outlet to the

high pressure turbine inlet arranged normally to be at least partially open, and means responsive to turbine speed for effecting closure of that valve and resultant cut off of the high pressure turbine steam supply when said speed reaches a given value, the combination of means for protecting said re heater against overheating by said combustion gases in the event of a closure of said high pressure turbine supply valve and consequent stoppage of flow through the re heater of the said discharge steam from the high pressure turbine outlet, said protecting means comprising a source of steam other than the aforesaid turbine outlet discharge and having a pressure higher than that of said discharge, a normally closed shut-off valve establishing connection from said other steam source to the re heater inlet, a relief valve establishing connection from the re heater outlet to the atmosphere, said relief valve being set to stay closed as long as the pressure within the re heater is at or below the aforesaid reduced value had by the steam normally entering the re heater from said high pressure turbine outlet and to open when the pressure within the re heater rises to or above that had by steam from said other steam source, and means rendered effective upon closure of said high pressure turbine supply valve for then opening said normally closed shut-off valve whereby then to supply into the re heater inlet steam from said other source which steam passes as a coolant through the re heater and thence to atmosphere by way of said relief valve now opened by the pressure of that steam.

4. In a system comprising a steam generator having a steam superheater and a steam re heater disposed therein to absorb heat from the combustion gases thereof, steam turbine apparatus including a high pressure stage connected to receive high pressure steam from the outlet of said superheater and arranged to discharge that steam at reduced pressure into the inlet of said re heater, said turbine apparatus further including a low pressure stage connected to receive said reduced pressure steam as discharged from the outlet of said re heater, a valve in the supply connection from the superheater outlet to the high pressure turbine inlet arranged normally to be at least partially open, and means responsive to turbine speed for effecting closure of that valve and resultant cut off of the high pressure turbine steam supply when said speed reaches a given value, the combination of means for protecting said re heater against overheating by said combustion gases in the event of a closure of said high pressure turbine supply valve and consequent stoppage of flow through the re heater of said discharge steam from the high pressure turbine outlet, said protecting means comprising a source of steam other than the aforesaid turbine outlet discharge, a normally closed shut-off valve establishing connection from said other steam source to the re heater inlet, a venting valve establishing connection from the re heater outlet to the atmosphere and organized to be closed as long as said reduced pressure steam flows from the high pressure turbine outlet through the re heater into the low pressure turbine inlet, means rendered effective upon closure of said high pressure turbine supply valve for then opening said normally closed shut-off valve whereby then to supply steam from said other source to the re heater inlet, check valve means in the discharge connection from the high pressure turbine outlet to the re heater inlet

effective to prevent said thus supplied other source steam from reversely flowing into that outlet in by pass relation to the re heater, and means effective upon admission through said shut-off valve of said other source steam into the re heater inlet for then opening said venting valve thereby allowing that other source steam to pass as a coolant through the re heater for escape to atmosphere by way of the re heater outlet and the venting valve.

5. In a system comprising a steam generator having a steam superheater and a steam re heater disposed therein to absorb heat from the combustion gases thereof, steam turbine apparatus including a high pressure stage connected to receive high pressure steam from the outlet of said superheater and arranged to discharge that steam at reduced pressure into the inlet of said re heater, said turbine apparatus further including a low pressure stage connected to receive said reduced pressure steam as discharged from the outlet of said re heater, a valve in the supply connection from the superheater outlet to the high pressure turbine inlet arranged normally to be at least partially open, and means responsive to turbine speed for effecting closure of that valve and resultant cut off of the high pressure turbine steam supply when said speed reaches a given value, the combination of means for protecting said re heater against overheating by said combustion gases in the event of a closure of said high pressure turbine supply valve and consequent stoppage of flow through the re heater of the said discharge steam from the high pressure turbine outlet, said protecting means comprising a source of steam other than the aforesaid turbine outlet discharge and having a pressure higher than that of said discharge, a normally closed shut-off valve establishing connection from said other steam source to the re heater inlet, a relief valve establishing connection from the re heater outlet to the atmosphere, said relief valve being set to stay closed as long as the pressure within the re heater is at or below the aforesaid reduced value had by the steam normally entering the re heater from said high pressure turbine outlet and to open when the pressure within the re heater rises to or above that had by steam from said other steam source, means rendered effective upon closure of said high pressure turbine supply valve for then opening said normally closed shut-off valve whereby then to supply into the re heater inlet steam from said other source which steam passes as a coolant through the re heater and thence to atmosphere by way of said relief valve now opened by the pressure of that steam, and a check valve in the discharge connection from the high pressure turbine outlet to the re heater inlet effective to prevent said thus supplied other source steam from reversely flowing into that outlet in by pass relation to the re heater.

6. In a system comprising a steam generator having a steam superheater and a steam re heater disposed therein to absorb heat from the combustion gases thereof, steam turbine apparatus including a high pressure stage connected to receive high pressure steam from the outlet of said superheater and arranged to discharge that steam at reduced pressure into the inlet of said re heater, said turbine apparatus further including a low pressure stage connected to receive said reduced pressure steam as discharged from the outlet of said re heater, a valve in the supply connection from the superheater outlet

to the high pressure turbine inlet arranged normally to be at least partially open, and means responsive to turbine speed for effecting closure of that valve and resultant cut off of the high pressure turbine steam supply when said speed reaches a given value, the combination of means for protecting said reheater against overheating by said combustion gases in the event of a closure of said high pressure turbine supply valve and consequent stoppage of flow through the reheater of said discharge steam from the high pressure turbine outlet, said protecting means comprising a source of steam other than the aforesaid turbine outlet discharge, a normally closed shut-off valve establishing connection from said other steam source to the reheater inlet, a normally closed venting valve establishing connection from the reheater outlet to the atmosphere, means rendered effective upon closure of said high pressure turbine supply valve for then opening both said shut-off valve and said venting valve whereby then to admit into the reheater inlet steam from said other source which steam passes as a coolant through the reheater and escapes to atmosphere by way of the venting valve, and a check valve in the discharge connection from the high pressure turbine outlet to the reheater inlet effective to prevent said thus supplied other source steam from reversely flowing into that outlet in by pass relation to the reheater.

7. In a system comprising a steam generator having a steam superheater and a steam reheater disposed therein to absorb heat from the combustion gases thereof, steam turbine apparatus including a high pressure stage connected to receive high pressure steam from the outlet of said superheater and arranged to discharge that steam at reduced pressure into the inlet of said reheater, said turbine apparatus further including a low pressure stage connected to receive said reduced pressure steam as discharged from the outlet of said reheater, and inlet valve in the supply connection from the superheater outlet to the high pressure turbine inlet arranged normally to be at least partially open, a normally open stop valve also disposed in said supply connection in series with said inlet valve, and means responsive to turbine speed for effecting closure of said inlet valve when said speed reaches a first given value and for further effecting closure of said stop valve when said speed reaches a second given value, the combination of means for protecting said reheater against overheating by said combustion gases in the event of a closure of either of said turbine inlet and stop valves, said protecting means comprising a source of steam other than the aforesaid discharge from the high pressure turbine outlet, a normally closed shut-off valve establishing connection from said other steam source to the reheater inlet, a venting valve establishing connection from the reheater outlet to the atmosphere and organized to be closed as long as said reduced pressure steam flows from the high pressure turbine outlet through the reheater into the low pressure turbine inlet, control means for said normally closed shut-off valve organized to effect a delayed opening of that valve upon closure of said turbine inlet valve and to effect a more prompt opening of the shut-off valve upon closure of said turbine stop valve whereby in either event steam from said other source will be supplied to the reheater inlet, check valve means in the discharge connection from the high pressure turbine outlet to the reheater inlet effective to prevent the thus supplied other source steam from reversely flowing into that outlet in by pass relation to the reheater, and means further effective upon closure of said turbine inlet valve for then opening said venting valve thereby allowing the said other source steam supplied as aforesaid to the reheater inlet to pass as a coolant through the reheater and escape to atmosphere by way of the reheater outlet and the venting valve.

pressure turbine outlet to the reheater inlet effective to prevent said thus supplied other source steam from reversely flowing into that outlet in by pass relation to the reheater, and means effective upon admission through said shut-off valve of said other source steam into the reheater inlet for then opening said venting valve thereby allowing that other source steam to pass as a coolant through the reheater and escape to atmosphere by way of the reheater outlet and the venting valve.

8. In a system comprising a steam generator having a steam superheater and a steam reheater disposed therein to absorb heat from the combustion gases thereof, steam turbine apparatus including a high pressure stage connected to receive high pressure steam from the outlet of said superheater and arranged to discharge that steam at reduced pressure into the inlet of said reheater, said turbine apparatus further including a low pressure stage connected to receive said reduced pressure steam as discharged from the outlet of said reheater, an inlet valve in the supply connection from the superheater outlet to the high pressure turbine inlet arranged normally to be at least partially open, a normally open stop valve also disposed in said supply connection in series with said inlet valve, and means responsive to turbine speed for effecting closure of said inlet valve when said speed reaches a first given value and for further effecting closure of said stop valve when said speed reaches a second given value, the combination of means for protecting said reheater against overheating by said combustion gases in the event of a closure of either of said turbine inlet and stop valves, said protecting means comprising a source of steam other than the aforesaid discharge from the high pressure turbine outlet, a normally closed shut-off valve establishing connection from said other steam source to the reheater inlet, a normally closed venting valve establishing connection from the reheater outlet to the atmosphere, control means for said normally closed shut-off valve organized to effect a delayed opening of that valve upon closure of said turbine inlet valve and to effect a more prompt opening of the shut-off valve upon closure of said turbine stop valve whereby in either event steam from said other source will be supplied to the reheater inlet, check valve means in the discharge connection from the high pressure turbine outlet to the reheater inlet effective to prevent the thus supplied other source steam from reversely flowing into that outlet in by pass relation to the reheater, and means further effective upon closure of said turbine inlet valve for then opening said venting valve thereby allowing the said other source steam supplied as aforesaid to the reheater inlet to pass as a coolant through the reheater and escape to atmosphere by way of the reheater outlet and the venting valve.

9. In a steam power generating station, a steam generator, a high pressure stage of a steam turbine and a low pressure stage, a steam superheater and a steam reheater associated with the steam generator, a first conduit for conveying steam from the steam generator to the inlet of the superheater, a second conduit connecting the superheater outlet with the high pressure stage steam turbine inlet, a turbine steam admission valve in said second conduit, means responsive to turbine speed for effecting automatic closure of that valve when said speed reaches a predetermined value, a third conduit connecting the high pressure stage turbine outlet with the inlet of the

reheater and a check valve in said conduit to prevent reverse flow of steam therethrough, a fourth conduit connecting the reheater outlet with the low pressure stage turbine inlet, a relief valve in said fourth conduit for at proper times venting steam therefrom to the atmosphere, a fifth conduit interconnecting a source of reheater cooling steam with the reheater inlet through said third conduit, a normally closed shut-off valve in said fifth conduit, and means rendered effective upon closure of said turbine admission valve for then opening said shut-off valve whereby upon interruption of the steam flow to the high pressure stage of the turbine by said turbine valve closure the aforesaid shut-off valve in the fifth conduit will open and admit steam from said reheater cooling source into the reheater inlet and thereby cause that steam to pass as a coolant through the reheater and out to the atmosphere through the relief valve in the fourth conduit.

10. In a steam power generating station, a steam generator, a high pressure stage of a steam turbine and a low pressure stage, a steam superheater having low and high temperature sections and a desuperheater therebetween with respect to steam flow and a steam reheater all associated with the steam generator, a first conduit for conveying steam from the steam generator to the inlet of the superheater, conduits interconnecting the desuperheater with the superheater sections, a second conduit connecting the superheater outlet with the high pressure stage steam turbine inlet, a turbine steam admission valve in said second conduit, means responsive to turbine speed for effecting automatic closure of that valve when said speed reaches a predetermined value, a third conduit connecting the high pressure stage turbine outlet with the inlet of the reheater and a check valve in said conduit to prevent reverse flow of steam therethrough, a fourth conduit connecting the reheater outlet with the low pressure stage turbine inlet, a relief valve in said fourth conduit for at proper times venting steam therefrom to the atmosphere, a fifth conduit interconnecting the desuperheater with the reheater inlet through said third conduit, a normally closed shut-off valve in said fifth conduit, and means rendered effective upon closure of said turbine admission valve for then opening said shut-off valve whereby upon interruption of the steam flow to the high pressure stage of the turbine by said turbine valve closure the aforesaid shut-off valve in the fifth conduit will open and admit steam from the said desuperheater into the reheater inlet and thereby cause that steam to pass as a coolant through the reheater and out to the atmosphere through the relief valve in the fourth conduit.

11. In a steam power generating station, a steam generator, a high pressure stage of a steam turbine and a low pressure stage, a steam superheater and a steam reheater associated with the steam generator, a boiler room steam main for supplying steam at lower pressure than does the steam generator, a first conduit for conveying steam from the steam generator to the inlet of the superheater, a second conduit connecting the superheater outlet with the high pressure stage steam turbine inlet, a turbine steam admission valve in said second conduit, means responsive to turbine speed for effecting automatic closure of that valve when said speed reaches a predetermined value, a third conduit connecting the high pressure stage turbine out-

let with the inlet of the reheater and a check valve in said conduit to prevent reverse flow of steam therethrough, a fourth conduit connecting the reheater outlet with the low pressure stage turbine inlet, a relief valve in said fourth conduit for at proper times venting steam therefrom to the atmosphere, a fifth conduit interconnecting said boiler room steam main with the reheater inlet through said third conduit, a normally closed shut-off valve in said fifth conduit, and means rendered effective upon closure of said turbine admission valve for then opening said shut-off valve whereby upon interruption of the steam flow to the high pressure stage of the turbine by said turbine valve closure the aforesaid shut-off valve in the fifth conduit will open and admit steam from the said boiler room steam main into the reheater inlet and thereby cause that steam to pass as a coolant through the reheater and out to the atmosphere through the relief valve in the fourth conduit.

12. In a steam power generating station, a steam generator, a high pressure steam turbine, a low pressure steam turbine, a steam superheater and a steam reheater associated with the steam generator, a first conduit for conveying steam from the steam generator to the inlet of the superheater, a second conduit connecting the superheater outlet with the high pressure steam turbine inlet, a turbine steam admission valve in said second conduit, means responsive to turbine speed for effecting automatic closure of that valve when said speed reaches a predetermined value, a third conduit connecting the high pressure steam turbine outlet with the inlet of the reheater and a check valve in said conduit to prevent reverse flow of steam therethrough, a fourth conduit connecting the reheater outlet with the low pressure steam turbine inlet, a relief valve in said fourth conduit for at proper times venting steam therefrom to the atmosphere, a fifth conduit interconnecting said first conduit leading from the steam generator with said third conduit leading to the reheater inlet, a normally closed shut-off valve in said fifth conduit, and means rendered effective upon closure of said turbine admission valve for then opening said shut-off valve whereby upon the interruption of steam flow to the high pressure steam turbine by said turbine valve closure the aforesaid shut-off valve in the fifth conduit will open and admit steam from the steam generator into the reheater inlet and thereby cause that steam to pass as a coolant through the reheater and out to the atmosphere through said relief valve in the fourth conduit.

13. In a steam power generating station, a steam generator, a high pressure stage of a steam turbine and a low pressure stage, a steam superheater and a steam reheater associated with the steam generator, a first conduit for conveying steam from the steam generator to the inlet of the superheater, a second conduit connecting the superheater outlet with the high pressure stage steam turbine inlet, a turbine steam admission valve in said second conduit, means responsive to turbine speed for effecting automatic closure of that valve when said speed reaches a predetermined value, a third conduit connecting the high pressure stage turbine outlet with the inlet of the reheater and a check valve in said conduit to prevent reverse flow of steam therethrough, a fourth conduit connecting the reheater outlet with low pressure stage turbine inlet, a normally closed venting valve

15

in said fourth conduit for at proper times releasing steam from the reheater outlet to the atmosphere, a fifth conduit connecting a source of reheater cooling steam with the reheater inlet through said third conduit, a normally closed shut-off valve in said fifth conduit, and means rendered effective upon closure of said turbine admission valve for then opening both said venting valve and said shut-off valve whereby upon interruption of the steam flow to the high pressure turbine by said turbine valve closure the aforesaid shut-off valve in the fifth conduit will open and admit steam from said reheater cooling source into the reheater inlet and thereby cause that steam to pass as a coolant through the reheater and out to the atmosphere through the venting valve in the fourth conduit.

14. In a steam power generating station, a steam generator, a high pressure steam turbine, a low pressure steam turbine, a steam superheater and a steam reheater associated with the steam generator, a first conduit for conveying steam from the steam generator to the inlet of the superheater, a second conduit connecting the superheater outlet with the high pressure steam turbine inlet, a stop valve and an inlet valve for said high pressure steam turbine in said second conduit, motor means for each of said valves organized to cause automatic closure of those respective valves in response to predetermined relative speeds of said high pressure steam turbine, a third conduit connecting the high pressure steam turbine outlet with the inlet of the reheater and a check valve in said conduit to prevent reverse flow of steam therethrough, a fourth conduit connecting the reheater outlet with the low pressure steam turbine inlet, a relief valve in said fourth conduit for at proper times venting steam from the reheater outlet to the atmosphere, a fifth conduit interconnecting the third conduit to a source of reheater cooling steam, a normally closed shut-off valve in said fifth conduit having a solenoid for opening said valve, a switch responsive to the position of the aforesaid turbine stop valve and a switch responsive to the position of the aforesaid turbine inlet valve, each switch being constructed and arranged to close with the closing of its respective turbine valve, and conductors connecting the switches in parallel and said shut-off valve solenoid in series with the switches into an electric control circuit whereby upon the interruption of steam flow to the high pressure steam turbine by the closing either of said stop or inlet valves the aforesaid shut-off valve in the fifth conduit will be opened to admit steam from the reheater cooling source into the reheater inlet and thereby cause that steam to pass as a coolant through the reheater and out to the atmosphere through the relief valve in the fourth conduit.

15. In a steam power generating station, a steam generator, a high pressure steam turbine, a low pressure steam turbine, a steam superheater and a steam reheater associated with the steam generator, a first conduit for conveying steam from the steam generator to the inlet of the superheater, a second conduit connecting the superheater outlet with the high pressure steam turbine inlet, a turbine steam admission valve in said second conduit, means responsive to turbine speed for effecting automatic closure of that valve when said speed reaches a predetermined value, a third conduit connecting the high pressure steam turbine outlet with the inlet of the reheater and a check

16

valve in said conduit to prevent reverse flow of steam therethrough, a fourth conduit connecting the reheater outlet with the low pressure steam turbine inlet, a relief valve in said fourth conduit for at proper times venting steam from the reheater outlet to the atmosphere, a fifth conduit interconnecting the third conduit to a source of reheater cooling steam, a normally closed shut-off valve in said fifth conduit having a solenoid for opening said valve, a switch responsive to the position of the aforesaid steam admission valve for the high pressure turbine constructed and arranged to close with the closing of that valve, conductors connecting said switch and said shut-off valve solenoid in series with an electrical control circuit whereby upon the interruption of steam flow to the high pressure steam turbine by closure of said turbine valve the aforesaid shut-off valve in the fifth conduit will be opened to admit steam from the reheater cooling source into the reheater inlet and thereby cause that steam to pass as a coolant through the reheater and out to the atmosphere through said relief valve in the fourth conduit, and a manually operable switch effective when closed to short circuit said first mentioned switch to thereby energize and optionally open said solenoid controlled cut off valve independently of said first mentioned switch.

16. In a steam power generating station, a steam generator, a high pressure stage of a steam turbine and a low pressure stage, a steam superheater and a steam reheater associated with the steam generator, a first conduit for conveying steam from the steam generator to the inlet of the superheater, a second conduit connecting the superheater outlet with the high pressure stage steam turbine inlet, a turbine steam admission valve in said second conduit, means responsive to turbine speed for effecting automatic closure of that valve when said speed reaches a predetermined value, a third conduit connecting the high pressure stage turbine outlet with the inlet of the reheater and a check valve in said conduit to prevent reverse flow of steam therethrough, a fourth conduit connecting the reheater outlet with the low pressure stage turbine inlet, a relief valve in said fourth conduit for at proper times venting steam from the reheater outlet to the atmosphere, a fifth conduit connecting the third conduit to a source of reheater cooling steam, a normally closed shut-off valve in said fifth conduit, motor means organized to open said shut-off valve and having associated therewith response-delay means which retard each valve opening for a predetermined period, and means rendered effective upon closure of said turbine admission valve for then activating said motor means whereby upon interruption of the steam flow to the high pressure turbine by said turbine valve closure the aforesaid shut-off valve in the fifth conduit will open after a predetermined period and then admit steam from the reheater cooling source into the reheater inlet for passage as a coolant through the reheater and out to the atmosphere through said relief valve in the fourth conduit.

17. In a steam power generating station, a steam generator, a high pressure stage of a steam turbine and a low pressure stage, a steam superheater and a steam reheater associated with the steam generator, a first conduit for conveying steam from the steam generator to the inlet of the superheater, a second conduit connecting the superheater outlet with the high

pressure stage steam turbine inlet, a stop valve and an inlet valve for said turbine in said second conduit, motor means for each of said valves organized to cause automatic closure of those respective valves in response to predetermined speeds of said turbine, a third conduit connecting the high pressure stage turbine outlet with the inlet of the reheat and a check valve in said conduit to prevent reverse flow of steam therethrough, a fourth conduit connecting the reheat outlet with the low pressure stage turbine inlet, a relief valve in said fourth conduit for at proper times venting steam from the reheat outlet to the atmosphere, a fifth conduit connecting the third conduit to a source of reheat cooling steam, a normally closed shut-off valve in said fifth conduit having a solenoid for opening said valve, switches respectively responsive to the positions of said turbine stop and inlet valves in the second conduit, circuit means including a source of energy and conductors interconnecting the switches with the aforesaid shut-off valve solenoid and with the energy source for causing the respective closing of said stop and inlet valves to establish individual paths of current flow to said solenoid, a normally open switch in the conductor interconnecting said inlet valve switch with the shut-off valve solenoid, a closing solenoid for said switch energized over said inlet valve switch, and means retarding the closure of the solenoid operated switch for a predetermined period whereby upon interruption of the steam flow to the high pressure turbine by the closure of said inlet valve the aforesaid shut-off valve in the fifth conduit will open after a predetermined period while upon interruption of the steam flow by the turbine stop valve said shut-off valve will open immediately, in either of which events the thus opened shut-off valve will admit steam from said reheat cooling source into the reheat inlet for passage as a coolant through the reheat and out to the atmosphere through the relief valve in the fourth conduit.

18. In a steam power generating station, a steam generator, a high pressure stage of a steam turbine and a low pressure stage, a steam superheater and a steam reheat associated with the steam generator, a first conduit for conveying steam from the steam generator to the inlet of the superheater, a second conduit connecting the superheater outlet with the high pressure stage steam turbine inlet, a turbine inlet valve in said second conduit, means responsive to turbine speed for effecting automatic closure of that valve when said speed reaches a predetermined value, a third conduit connecting the high pressure stage turbine outlet with the inlet of the reheat and a check valve in said conduit to prevent reverse flow of steam therethrough, a fourth conduit connecting the reheat outlet with the low pressure stage turbine inlet, a normally closed venting valve in said fourth conduit for at proper times releasing steam from the reheat outlet to the atmosphere, a solenoid for opening said venting valve, a fifth conduit connecting a source of reheat cooling steam with the reheat inlet through said third conduit, a normally closed shut-off valve in said fifth conduit, a solenoid for opening said shut-off valve, a switch responsive to the position of the aforesaid turbine inlet valve, circuit means including conductors interconnecting said switch with said shut-off valve solenoid and said venting valve solenoid and with a source of energy where-

by closure of said inlet valve will cause said switch to establish individual paths of current flow to said two solenoids and thereby open the shut-off and venting valves, a normally open switch in the conductor interconnecting said inlet valve switch with the shut-off valve solenoid, a closing solenoid for said switch energized over said inlet valve switch, and means retarding the closure of the solenoid operated switch for a predetermined period whereby upon interruption of the steam flow to the high pressure turbine by the closure of said inlet valve the aforesaid venting valve in the fourth conduit will immediately open while the aforesaid shut-off valve in the fifth conduit will open after a predetermined period, whereupon the thus opened shut-off valve will admit steam from said reheat cooling source in the reheat inlet for passage as a coolant through the reheat and out to the atmosphere by way of the opened venting valve.

19. In a steam power generating station, a steam generator, a high pressure stage of a steam turbine and a low pressure stage, a steam superheater and a steam reheat associated with the steam generator, a first conduit for conveying steam from the steam generator to the inlet of the superheater, a second conduit connecting the superheater outlet with the high pressure stage steam turbine inlet, a turbine inlet valve in said second conduit, means responsive to turbine speed for effecting automatic closure of that valve when said speed reaches a predetermined value, a third conduit connecting the high pressure stage turbine outlet with the inlet of the reheat and a check valve in said conduit to prevent reverse flow of steam therethrough, a fourth conduit connecting the reheat outlet with the low pressure stage turbine inlet, a normally closed venting valve in said fourth conduit for at proper times releasing steam from the reheat outlet to the atmosphere, a solenoid for opening said venting valve, a fifth conduit connecting a source of reheat cooling steam with the reheat inlet through said third conduit, a normally closed shut-off valve in said fifth conduit, a solenoid for opening said shut-off valve, a switch responsive to the position of the aforesaid turbine inlet valve, circuit means including conductors interconnecting said switch with said shut-off valve solenoid and said venting valve solenoid and with a source of energy whereby closure of said inlet valve will cause said switch to establish individual paths of current flow to said two solenoids and thereby open the shut-off and venting valves, so that upon interruption of the steam flow to the high pressure turbine by the closure of said inlet valve said shut-off valve in the fourth conduit and said venting valve in the fifth conduit will both open and cause steam from said reheat cooling source to be admitted into the reheat inlet for passage as a coolant through the reheat and out to the atmosphere by way of the venting valve, a pressure responsive switch in the conductor interconnecting said inlet valve switch with the venting valve solenoid, and means responsive to the pressure in said reheat to open said pressure responsive switch when the said pressure reduces to about atmospheric and thereby close said venting valve when need for holding same open no longer exists.

20. In a steam power generating station, a steam generator, a high pressure stage of a steam turbine and a low pressure stage, a steam superheater and a steam reheat associated with

the steam generator, a first conduit for conveying steam from the steam generator to the inlet of the superheater, a second conduit connecting the superheater outlet with the high pressure stage steam turbine inlet, a stop valve and an inlet valve for said turbine in said second conduit, motor means for each of said valves organized to cause automatic closure of those respective valves in response to predetermined speeds of said turbine, a third conduit connecting the high pressure stage turbine outlet with the inlet of the reheater and a check valve in said conduit to prevent reverse flow of steam therethrough, a fourth conduit connecting the reheater outlet with the low pressure stage turbine inlet, a normally closed venting valve in said fourth conduit for at proper times releasing steam from the reheater outlet to the atmosphere, a solenoid for opening said venting valve, a fifth conduit connecting a source of reheater cooling steam with the reheater inlet through said third conduit, a normally closed shut-off valve in said fifth conduit, a solenoid for opening said shut-off valve, switches respectively responsive to the positions of said turbine stop and inlet valves in the second conduit, circuit means including a source of energy and conductors connecting both the venting valve solenoid and the shut-off valve solenoid to that source through said inlet valve switch and said shut-off valve solenoid further to that source through said stop valve switch, said stop valve switch having two branches one of which

5
